Primary Examiner — Susan Moon Lee(74) *Attorney, Agent, or Firm* — Dunlap, Bennett & Ludwig PLLC(57) **CLAIM**

The ornamental design for a gameboard, as shown and described.

DESCRIPTION

FIG. 1 is a top perspective view of a gameboard; and, FIG. 2 is a top plan view thereof. The broken lines shown in the drawings illustrate portions of the gameboard that form no part of the claimed design.

1 Claim, 2 Drawing Sheets(56)
